UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

METHOD OF MAKING SHOES.

1,065,584.

Specification of Letters Patent.

Patented June 24, 1913.

Original application filed December 13, 1910, Serial No. 597,055. Divided and this application filed February 24, 1913. Serial No. 750,279.

To all whom it may concern:

Be it known that I, MATTHIAS BROCK, a citizen of the United States, residing at Boston, in the county of Suffolk and State 5 of Massachusetts, have invented certain Improvements in Methods of Making Shoes, of which the following description, in connection with the accompanying drawings, is a specification, like reference characters 10 on the drawings indicating like parts in the several figures.

This invention relates to methods of making shoes and consists in certain improvements by which the mounting of uppers and 15 previously connected soles or insoles upon the shoe lasts is facilitated.

The invention is shown in connection with the manufacture of stitch-down shoes by a well-known system in which the upper and 20 the sole or insole are permanently connected off the last and the last is then inserted to distend and shape the shoe. The invention is also applicable to the remounting of turn or other shoes upon lasts in the systems of 25 making shoes in which that operation is performed. This is labor requiring much strength and a considerable amount of skill to obtain the best results and avoid tearing or permanently distorting the stock or overstraining seams.

In accordance with this invention, after a last has been partially inserted into the toe portion of a shoe as far as it will readily go, the shoe is engaged in the crease between 35 the upper and the projecting edge of the sole, herein called the "welt crease," at the toe and relative movement is effected by which pressure is applied lengthwise of the shoe in the direction to complete the mounting 40 of the forepart of the shoe on the last. Advantageously the forepart of the sole face may also be engaged and rearwardly directed pressure applied thereto to assist in forcing the shoe onto the last. If the rearwardly directed movement of the sole is made before or is greater than the movement of the stock in and about the welt crease the sole can thus be made to draw the attached upper upwardly over the toe of the 45 last held in inverted position for correctly positioning the welt crease at the toe relatively to the plane of the last bottom. Advantageously also the heel end of the shoe 50 may be pulled rearwardly and downwardly

over the heel end of the last while the backward pressure on the forepart of the shoe is being applied.

The invention will now be further explained in connection with the accompanying drawings and will then be pointed out 60 in the claims.

Figure 1 shows a shoe upper and attached sole with a last entered into the toe portion thereof. Fig. 2 shows said shoe engaged in the welt crease around the toe and 65 also engaged upon the forepart of the sole face and the upper is being drawn up around the toe end of the last by rearwardly directed pressure applied to the sole face. Fig. 3 shows the shoe being moved rearwardly on the last by continued backwardly directed pressure applied to the sole face simultaneously with rearward pressure applied in the welt crease and also the welt 70 crease being shaped by the pressure applied 75 therein. This figure also shows the heel portion of the shoe being drawn down over the heel end of the last while the pressure on the forepart of the shoe is being applied, or is maintained. Fig. 4 shows the shoe at the 80 end of this operation.

The practice of the invention will be explained with the aid of the apparatus herein shown, which is the novel apparatus claimed in a co-pending application Ser. No. 597,055, 85 filed Dec. 13, 1910, for a machine for mounting shoes, and from which application this present application is a division. It will be understood, however, that this present invention is not dependent upon the use of the 90 illustrated mechanism or of any particular form of mechanism.

The shoe is received with the upper 1 and the sole 2 connected, usually by a seam of stitches, as in Fig. 1 and the forepart is applied to its last 3, as there shown, to such an extent as can readily and quickly be done. The shoe, with the last suitably supported, is then engaged in the welt crease 4, as by the plates 5, and preferably also upon the sole 100 face of its forepart, as by the toothed presser 6 in Fig. 2, and pressure toward the heel is applied at these points. The rearward pressure or movement applied through the sole may well exceed or precede that applied 105 through the welt crease and in that event it will result in drawing up the toe portion of the shoe toward the plane of the last bottom

as it is usually desirable to do in order to locate the shoe stock correctly at the toe of the last. Continued rearward pressure through the sole and the welt crease will 5 force the forepart of the upper upon the forepart of the last as in Fig. 4. The described application of pressure may be followed, but preferably will be accompanied, by a movement of the rear portion of the 10 shoe downwardly, and it may also advantageously be rearwardly, over the heel portion of the last. This may be effected by engaging the rear part of the shoe, as for example between the rear end of the last and 15 the inside face of the shoe, by a blade or a spoon shaped device 7 and drawing the shoe stock downwardly by movement of said device. Obviously the workman may use his hands instead of the devices 5, 6, 7 to apply 20 force as described which will move the shoe parts relatively to the last as indicated by the arrows on the drawings to force first the forepart and then the heel part of the shoe upon its last and in so doing to stretch or 25 distend the shoe stock to the shape of the last. The application of pressure as described through the plates 5, which preferably embrace the toe from one side around the end to the other side of the toe, shapes 30 or reshapes the welt crease around the toe as an incident to the mounting of the shoe on the last. Advantageously the sole face of the shoe may be engaged at or near the toe end of the sole and also over the ball of 35 the last and the rearward pressure applied at these two points as shown.

Having explained the nature of this invention and described how it may be practised, I claim as new and desire to secure by 40 Letters Patent of the United States:—

1. That improvement in methods of making shoes which consists in entering a last into the toe portion of a shoe the upper of which has previously been connected with 45 the sole, engaging the shoe in the welt crease at the toe and also engaging it on the sole face of its forepart, and applying pressure lengthwise of the shoe in the direction to complete the mounting of the forepart of 50 the shoe on the last.

2. That improvement in methods of making shoes which consists in entering a last into the toe portion of a shoe, engaging the shoe in the welt crease around the toe and 55 also engaging it at the toe end of its sole face and also over the ball and, while sustaining the last, effecting rearward pressure

upon the shoe simultaneously in said crease and on the sole face until the toe of the shoe is mounted on the toe of the last and the 60 crease is shaped.

3. That improvement in methods of making shoes which consists in entering a last into the toe portion of a shoe the upper of which has previously been connected with 65 the sole, engaging the shoe in the welt crease at the toe, and applying pressure lengthwise of the shoe in the direction to complete the mounting of the forepart of the shoe on the last. 70

4. That improvement in methods of making shoes which consists in entering a last into the toe portion of a shoe, engaging the shoe in the welt crease at the toe and also engaging it on the sole face of the forepart, 75 moving the sole backwardly to draw the attached upper upwardly over the toe of the inverted last, and applying relative pressure to the last on one hand and both to the crease and the sole on the other hand in a direction 80 lengthwise of the shoe to force the toe portion of the shoe and the last together.

5. That improvement in methods of making shoes which consists in entering a last into the toe portion of a shoe, engaging the 85 shoe in the welt crease at the toe and also engaging it on the sole face of the forepart, and applying pressure lengthwise of the shoe in the direction to complete the mounting of the forepart of the shoe on the last 90 and, while such pressure is being exerted, pulling rearwardly and downwardly on the heel end of the shoe relatively to the inverted last.

6. That improvement in methods of making 95 shoes which consists in entering a last into the toe portion of a shoe the upper of which has previously been connected with the sole, engaging the shoe in the welt crease at the toe and also engaging it on the sole face of the forepart, drawing the toe end of the upper up over the toe end of the inverted last, then drawing the toe of the shoe backwardly about the toe of the last by pressure applied in the welt crease and 100 105 backward draft on the sole face.

In testimony whereof I have signed my name to this specification in the presence of two subscribing witnesses.

MATTHIAS BROCK.
